Inventor
DOMENICK M. CUA

By

C. H. Parker, Attorney

UNITED STATES PATENT OFFICE.

DOMENICK M. CUA, OF SANDUSKY, OHIO.

CUE HOLDER.

1,416,617.

Specification of Letters Patent. Patented May 16, 1922.

Application filed June 6, 1921. Serial No. 475,413.

To all whom it may concern:

Be it known that I, DOMENICK M. CUA, a citizen of the United States, residing at Sandusky, in the county of Erie and State of Ohio, have invented certain new and useful Improvements in Cue Holders, of which the following is a specification.

This invention relates to cue holders, and more particularly to racks for retaining billiard cues when not in use.

An object of the present invention is the provision of an individual casing or rack wherein the owner of a cue may keep it when not in use and prevent its use by others.

A further object of the invention is the provision of a rack comprising a member adapted to surround the cue to protect it from dampness and keep it clean and dry. The portion surrounding the cue is provided with suitable lining of soft material, such as felt or fabric, which protects the cue from exposure to dampness and prevents the tip from becoming loosened when the cut is not in use. The device further serves as a cue straightener, tending to straighten the cue when in the rack.

In one embodiment of the invention, I provide suitable supporting mechanism whereby the device may be secured to a wall or other support, and a sleeve formed in two hinged sections is arranged on the support. The sleeve is adapted to surround the upper portion of the cue and is closed at the top, the lower end of the cue being received in a bracket spaced from the bottom of the sleeve.

In the accompanying drawings, I have shown one embodiment of the invention. In this showing:

Figure 1 is a front elevation showing the rack in closed position,

Figure 2 is a similar view showing the rack in open position,

Figure 3 is a side elevation,

Figure 4 is a horizontal sectional view on line 4—4 of Figure 1,

Figure 5 is a similar view on line 5—5 of Figure 1, and,

Figure 6 is a horizontal sectional view on line 6—6 of Figure 1.

Referring to the drawings, the reference numeral 1 designates suitable longitudinal supporting strips adapted to be secured to a wall 2 or other support. These strips are

connected by cross members 3, suitably spaced from each other and arranged adjacent the top of the holder. The cross strips 3 are provided with recesses 4, substantially semi-circular in shape and adapted to receive the fixed section 5 of the sectional sleeve. As shown, the sleeve comprises an outer casing of aluminum or other suitable material having a lining 7, of felt or other material which will not mar the cue. A movable section 8 is secured to the fixed section of the sleeve by means of hinges 9, the movable section being constructed similarly to the fixed section. As shown, the upper ends of the two sections are rounded, as at 10, whereby the upper end of the sleeve is closed when the movable section is arranged in closed position. Suitable means may be employed for locking the sleeve in closed position. As shown, a band 11, formed of two substantially semi-cylindrical portions and secured to each other by means of a hinge 12 is arranged about the sleeve, one of the sections being secured to each half of the sleeve. The free ends of the sections 13, of the band are provided with offset portions 14, adapted to align with each other when the sleeve is in closed position. A padlock or other suitable locking means may be secured in said openings.

The lower end of the longitudinal strips are connected by a cross piece 16, comprising a substantially flat section or base and having an outer flange 17, as shown.

When the cue is to be placed in the rack, the holder or sleeve is arranged in open position and the lower end of the cue first inserted behind the flange 17. The upper end of the cue is then inserted in the fixed section of the sleeve and the rack closed and locked. It will be apparent that when the movable section 8 of the sleeve is in closed position, the cue is retained therein against removal, as the lower end of the cue cannot be removed, due to the flange 17. It is first necessary to open the sleeve or holder and remove the upper end of the cue from the rack, thus permitting the lower end to be removed by slightly raising the cue.

It is to be understood that the form of my invention herewith shown and described is to be taken as a preferred example of the same, and that various changes in the shape, size, and arrangement of parts may be re-

sorted to without departing from the spirit of the invention or the scope of the subjoined claims.

Having thus described my invention, I claim:

1. A cue holder comprising a pair of supporting strips, cross members connecting said strips, a substantially semi-cylindrical sleeve section supported on said cross members, a substantially semi-cylindrical sleeve section hinged thereto and adapted to cooperate with said first section to form a sleeve for the reception of the cue, said sleeve being provided with a closed end and an open end, and a supporting member spaced from said open end and arranged in alinement with said sleeve.
- 15 2. A cue holder comprising a pair of

longitudinal members, transverse members connecting said longitudinal members, a substantially semi-cylindrical sleeve section mounted on said transverse members, a second semi-cylindrical sleeve hinged thereto, said sleeve sections being closed at one end, and a supporting base arranged in alinement with said fixed sleeve section and adapted to receive the end of the cue, said supporting base being provided with an upstanding flange to prevent the end of the cue from being removed therefrom.

In testimony whereof I affix my signature in presence of two witnesses.

DOMENICK M. CUA.
